MINE CAR COUPLING

Dewey O. Turner, Pine Grove, Calif.

Application December 26, 1947, Serial No. 143,373

Term of patent 7 years

(Cl. D66—2)

To all whom it may concern:

Be it known that I, Dewey O. Turner, a citizen of the United States, residing at Pine Grove, county of Placer, State of California, have invented a new, original, and ornamental Design for a Mine Car Coupling, of which the following is a specification, referring to the accompanying drawing, forming part thereof.

Figure 1 is a side elevation of the mine car coupling showing my new design.

Figure 2 is a fragmentary top plan view of the coupling showing my new design.

I claim:

The ornamental design for a mine car coupling, substantially as shown.

DEWEY O. TURNER.
